DESIGN FOR A LOCK FOR LUGGAGE CONTAINERS OR THE LIKE

Abraham Levine, Elizabeth, N. J.

Application April 1, 1941, Serial No. 100,078

Term of patent 14 years

To all whom it may concern:

Be it known that I, Abraham Levine, a citizen of the United States, residing in Elizabeth, county of Union, and State of New Jersey, have invented a new, original, and ornamental Design for a Lock for Luggage Containers or the like, of which the following is a specification, reference being had to the accompanying drawing, forming part thereof.

In said drawing, Fig. 1 is a top plan view, Fig. 2 is a side edge view, and Fig. 3 is a front elevational view, of a lock for luggage containers or the like, showing my new design.

I claim:

The ornamental design for a lock for luggage containers or the like, as shown.

ABRAHAM LEVINE.
